UNITED STATES PATENT OFFICE.

JOHN L. TAPLIN, OF CIRCLEVILLE, ASSIGNOR TO JOSEPH A. JEFFREY,
OF COLUMBUS, OHIO.

DRIVE-CHAIN.

SPECIFICATION forming part of Letters Patent No. 508,258, dated November 7, 1893.

Application filed March 2, 1891. Serial No. 383,414. (No model.)

To all whom it may concern:

Be it known that I, JOHN L. TAPLIN, a citizen of the United States, residing at Circleville, in the county of Pickaway and State of Ohio, have invented certain new and useful Improvements in Drive-Chains, of which the following is a specification, reference being had therein to the accompanying drawings.

Figure 1 is a plan view of so much of a chain as is necessary to illustrate my invention. Fig. 2 is an edge view looking in the direction of the arrow, Fig. 1. Fig. 3 is a view of the pindle detached. Fig. 4 is a section on the line x, x , of Fig. 2.

15 A, B, C, is one of the side bars, the part A having a round seat for the pindle, with a transverse rib or shoulder a upon its outer face, the opposite end having an inward projecting sleeve C, adapted to receive an anti-friction 20 roller C'. While I prefer to have the rib or shoulder in the position shown in the drawings, such location is not indispensable, because it may be arranged upon the opposite or either of the other sides of the pindle seats 25 and in close proximity thereto. The pindle H has a head h at one end, which is flattened or slabbed off at one edge to form a shoulder, as at h' , so that when in working position the shoulder rib or stop a fits somewhat closely 30 to this slabbed off part and prevents the bolt from turning around in its seat in the end bar, to insure that the wear shall come upon that part of the pindle which is within the sleeve C, F. Of course the opposite end of the pindle should be riveted over or otherwise secured against accidental displacement. D E 35 F is the other side bar. This construction of parts, to effect the binding together of the several parts of the chain, to provide a perfect 40 articulation for one link in relation to that adjacent and for locking the pindle against rotation in the outside or overlapping and parts A, D, of the side bars, was devised for the purpose of overcoming the difficulties that 45 have been experienced in using the other construction of pindle, and adjacent parts heretofore commonly used. It has been the practice in making chains of this sort to form the aperture at a' or d' key-hole shaped, that is 50 to say with a circular part and an outwardly extending groove or recess communicating

therewith; and then form the pindle with a completely circular head at h and with a web or fin immediately inside of said head and integral therewith and with the pindle shank, 55 this web or fin being adapted to enter the aforesaid recess or slot part of the key-hole aperture in the side bar.

Now the side bars A B C and D E F are made of malleable castings, while the pintles 60 H are drop forgings.

When the parts are constructed as herein shown both the castings and the forgings can be made much more easily, rapidly and cheaply, than when they are formed in the way above 65 referred to and heretofore followed. It has been found to be a matter of difficulty to drop forge the pindle with the webs or fins under the heads, as the fins are necessarily small, relatively, and a large percentage of them (the 70 webs) tend to be malformed, and either too small or too large. They should be as large as possible in order to provide an efficient lock, but at the same time if they are too long by a mere fraction of an inch they strike against 75 the inside bars and prevent the forming of a compact joint and cause a binding at the place of articulation. Again, when the side bars at A, D, are formed with key-hole slots there is a 80 weakening of the metal, which is avoided when the locking is effected by means of the shoulder rib or metallic extension a herein provided, the link herein being made, in fact, stronger by the addition of the locking devices, instead of weaker.

It will be seen that the parts herein provided are adapted for use in the manufacture of chains of the stronger species, that is of the sorts which require that the links and coupling devices should be capable of standing 90 great strain and which should have as little looseness as possible at the places of articulation, in contra-distinction to those relatively weaker chains, for lighter work and which are constructed to allow a ready coupling and uncoupling of one link from another after turning them into unusual or non-working positions. A chain like that herein can have its links coupled or uncoupled from those adjacent without requiring that either should be 95 thrown out of working relation to another. The end h^2 can be readily reduced in size by 100

ordinary tools so as to permit the pintle to be withdrawn, without throwing the adjacent links out of position. So, too, the lug or projection *a* permits the pintle to be inserted 5 when its link and the adjacent one are in line. In this respect therefore the construction herein differs essentially from earlier ones such as are illustrated in patents to B. A. Legg, No. 376,325, dated January 10, 1888, and 10 No. 378,173 to B. Oborn, dated February 21, 1888.

I do not herein claim any of the subject-matter relating to the attachments which may be formed with or secured to the chain links, 15 and claimed in my Patent No. 425,467, dated April 15, 1890, granted on application, Serial No. 291,994, from which was withdrawn the matter for this application.

What I claim is—

20 1. The combination with the link having the overlapping side bars formed with an outwardly projecting shoulder or lug as at *a* and with the pintle seats on a line adjacent to the said shoulder, of the contiguous link having 25 the transverse pintle seat in line with the

aforesaid pintle seats, and the pintle having the head outside the links shouldered as at *h'* to lock against the said shoulder *a* to prevent its rotating in the outer pintle seats, said pintle and links being adapted to be coupled and 30 uncoupled while the links are in line with each other and in working position, substantially as set forth.

2. In a drive chain the combination with the side bars provided with tubular bearings 35 at one end and pintle seats at their opposite ends of removable pintles having heads overlapping the outer faces of the side bars, and stops projecting from and beyond the plane of the outer faces of the side bars, and engaging 40 with the pintles to prevent the pintles from rotating within their seats in the side bars, substantially as set forth.

In testimony whereof I affix my signature in presence of two witnesses.

JOHN L. TAPLIN.
